ELECTRICALLY HEATED DRYING OVEN FOR
YARN IMPREGNATING MACHINES

Webster Jones, deceased, late of New York, N. Y.,
by Mildred Andrew Jones, administratrix, New
York, N. Y., and John J. Heslin, Waltham,
Mass., assignors to Chemo-Textiles, Inc., a cor-
poration of Rhode Island

Application June 30, 1948, Serial No. 36,018

10 Claims. (Cl. 219—35)

1

This invention relates to apparatuses for impregnating yarns. The word "yarn" is used herein to designate those materials specifically referred to in the trade as yarns and in addition materials of similar form and properties, such as cord, twine, string, and thread, whether of staple fibers or continuous filaments. In one method for the impregnation of yarns they are contacted with the impregnating agent in solution or suspension, followed by heating to dry and/or cure the impregnating agent, for example by polymerizing it, after which the yarn is wound upon a spool for transfer to point of ultimate use. Suitable impregnating agents, depending upon the purpose for which the yarn is to be used, are rubber latex, partially polymerized resins, preferably of the urea formaldehyde type in aqueous solution or suspension, cellulose derivatives in organic solvents, vinyl-butyral or vinyl chloride in aqueous dispersion, copolymers of vinyl chloride and vinyl acetate in various ratios as solutions or dispersions, polyethylene in toluol or xylol, melamine formaldehyde and/or urea formaldehyde in aqueous dispersion.

The purposes for which the impregnation is applied include:

- (a) Oil or water resistance
- (b) Abrasion resistance
- (c) Mildew and vermin resistance
- (d) Increased strength
- (e) To set the twist thereby permitting the use of the yarns spun with less than the usual amount of twist
- (f) Shrinkage control
- (g) Reduction of fuzz
- (h) Control of residual stretch
- (i) Fire resistance

In all these cases the heating to dry and set or cure the impregnating agent must be done while the yarn is freely suspended, since the result would otherwise be to cement the yarn upon itself. Preferably the yarn is fed in individual spaced-apart form into contact with the impregnating agent, thence through the oven and thence to the winding spool. For economy of operation a number of yarns in spaced-apart form are usually fed through a common impregnating bath, thence through a common oven and thence to a winder containing a number of packages upon which the yarns are individually wound. This invention relates particularly to the oven for drying and setting or curing the impregnating agent and will be fully understood

2

from the following description read in conjunction with the drawings in which:

Fig. 1 is a diagrammatic longitudinal section through the complete contacting, heating and winding apparatus;

Fig. 2 is a top view of part of the construction shown in Fig. 1;

Fig. 3 is a detailed vertical section through part of the construction shown in Fig. 1;

Fig. 4 is a vertical section through the construction shown in Fig. 3 on the plane indicated by 4—4;

Fig. 5 is a detailed side view, with parts broken away, of the oven shown in Fig. 1;

Fig. 6 is a vertical section through the construction shown in Fig. 5 on the plane indicated by 6—6;

Fig. 7 is a detail of one element of the construction shown in Fig. 6, and

Fig. 8 is a detail of one element of the construction shown in Fig. 5.

Referring to Fig. 1, the yarn 1 to be impregnated enters the contacting apparatus 2, through guide 3, emerging after impregnation at 9 to enter the drying or curing oven 10, in which it is heated to temperature at which the solvent will be driven off and any desired change in the impregnating agent produced. After drying or curing it emerges from the oven at the point 100 to enter the winder 101 by which it is spooled.

Referring to Figs. 2, 3 and 4 for a detailed showing of the impregnating apparatus, tank 4 carries impregnating liquid 5, which is carried upwardly by roller 6, driven by shaft 7 projecting through the side wall of tank 4. Tank 4 is surmounted by a number of individual sections, such as 12 (Figs. 2 and 3). These are preferably formed of sheet metal and include vertically disposed side portion 13 and horizontally disposed top portion 14 (Figs. 2, 3 and 4). Each section is mounted at point 15 for pivotal movement about shaft 16 which is carried (Fig. 2) by brackets 17 and 18, mounted on flange 19 secured to side wall 20 of tank 4. Each individual section 12 may be independently tilted about the shaft 16 (Fig. 3) and the horizontal portions 14 collectively form a roof or cover over the tank (Fig. 2). Roller 21 (Fig. 3) is provided with the tire or rim 22 of resilient material, such as rubber, which rides upon and is driven by roller 6. Roller 21 is rotatably mounted on shaft 23 carried by bell arm 24. Bell arm 24 is pivotally secured to the side 13 of section 12 by rivet 25; the free end 26 of bell arm 24 is pivotally secured to the rod 27, which

is in turn connected to spring 28, secured by rivets 29 to the horizontal top portion 14 of section 12. The tension applied by spring 28 is adjustable by means of the screw 29. This provides an adjustable pressure between the rollers 6 and 21. Yarn 1 is fed into the bite 30 between these rollers by guide roll 31 pivotally mounted by stud 32 in side wall 13 of section 12. After emerging from the bite the yarn passes through wire loop guide 34 into the bite 35 between squeeze rollers 36 and 37. Roller 36 is rotatably mounted by stud 38 in side wall 13 of section 12 while squeeze roller 37 is rotatably mounted by stud 39 in bracket 41 carried by spring 42. The tension of spring 42 and therefore the pressure between squeeze rollers 36 and 37 is manually adjustable by the two screws 43 and 44 threaded into horizontal top portion 14 of section 12. Upon emerging from bite 35 of rollers 36 and 37 the yarn passes through an additional squeeze provided by the two stationary cones 45 and 46 of resilient material. Cone 45 is secured to the side wall 13 by bracket 47 held in position by screw 48, while cone 46 is carried by bracket 51 pivotally mounted by stud 52 on side wall 13. The pressure between cones 45 and 46 is adjustable by tension spring 53.

As is evident from the foregoing, any one of the sections 12 may be tilted about the shaft 16, thereby breaking contact between the rollers 6 and 21. While these are in contact, they draw yarn 1 into the bite 30 between said rollers and thereby feed the yarn into the impregnating apparatus. The tilting of the section by breaking this contact automatically stops the feed of the individual yarn controlled by the particular section.

The oven 101, which is employed to heat the contacted yarn, to dry the same and set or cure the impregnating agent has sides 102 and 103 (Fig. 6) formed of slabs of insulating material and a roof 104 also formed of slabs of insulating material and therefore defines an inverted open bottom trough 105. Inasmuch as a number of yarns are preferably fed simultaneously through the oven, it is preferred to provide a number of vertically oriented longitudinally extending fins 106 suspended from transverse rods 107, carried in side walls 102 and 103. Fins 106 are held in spaced relationship by spools 108 encircling rods 107 (Figs. 6 and 7). These fins divide the trough 105 into a number of parallel open bottom channels 109. While four such channels appear in a broken section shown in Fig. 6, in commercial practice a single oven may include 50 or even 100 such individual channels. The yarn 1, in freely suspended form, is drawn through the center portion of these channels by the winding apparatus 151. The oven is supported by the longitudinally extending angle irons 111 and 112 (Figs. 5 and 6) which are in turn carried by the longitudinally extending upright I-beams 113 and 114. For the purpose of transmitting the load onto the angle irons 111 and 112, the transverse rods 107 are extended through holes in angle irons 111 and 112 and secured in position by nuts 115 and 116. Each of the fins 106 is provided at its lower edge with a longitudinally extending offset 117 and with a channel-shaped stiffener 118 to minimize warping or buckling.

Means is provided for heating the interior of the trough 105 and while any suitable heating means may be employed, we preferably use a number of transversely arranged electrical re-

sistance heater elements 121. As shown in Fig. 6, each of these is supported at either end by a bracket, such as 122 or 123, secured at its outer end to one of the angle irons 111 and 112, and projecting inwardly through the respective side wall of the oven. The heater elements are mechanically secured to these brackets through suitable electrically insulated bushings 124.

The oven is relatively long and may, for example, have a length of from 20 to 50 feet. For the purpose of maintaining a uniform and controllable temperature within the oven, it was found that a spacing of the transversely extending heater elements 121 of approximately 8" centers, distributed along the length of the oven, is entirely satisfactory. In practice, the heater elements 121 are subdivided or grouped into several individual circuits, each including several resistor elements; each individual circuit is individually controlled, for example, by means of a thermostat operating through an electrical relay switch (not shown) so that the heat input from point to point along the length of the oven may be accurately adjusted to maintain a uniform temperature along the length of the oven or, if desired, to maintain zones of longitudinally increasing or longitudinally decreasing temperature. Suitable temperature measuring devices (not shown) are mounted at various points in the oven to apprise the operator of the exact temperature obtaining within each part of the oven.

Referring to Fig. 5, that part of the view indicated by a—a is a longitudinal section through the construction shown in Fig. 6 on the plane indicated by a—a. As shown, the heater elements 121 are centrally supported by the longitudinally extending strip 131 suspended from the roof 104 by the studs 132.

Referring to Fig. 5, that part of the view indicated by b—b is a view through the construction shown in Fig. 6 on the plane indicated by b—b, with a part broken away to show the longitudinal construction of the fins 106. As shown, these fins define a number of holes 133 adjacent their upper edges through which the rods 107 are passed and by which the fins are supported. These holes 133 are in the form of flat ellipses, the horizontal axis of which is considerably greater than the radius of the rods 107, thereby permitting the fins 106 to expand considerably in response to the applied heat without pressing horizontally against the rods 107. Any such pressure would result in a longitudinal warping of the fins, which would in turn cause the fin to make a rubbing contact with the yarn in passing through channel 109 and by building up a deposit of the impregnating material, would interfere with the successful operation of the oven. The fins are also supplied with a longitudinal open space 134 between the ends of adjacent fins, so that they may expand freely without interference with one another.

Referring again to Fig. 5, that part of the figure indicated by c—c is a showing through part of the construction shown in Fig. 6 on the plane indicated by c—c.

As indicated in Fig. 5, the oven 101 is provided with end closures 135 and 136 defining respectively apertures 137 and 138 through which the yarn 1 passes.

With certain impregnating agents the temperature in the oven need only be sufficient to dry out the solution of the impregnating agent, leaving the impregnating agent within the fibers of the

yarn. With other impregnating agents a higher temperature is employed for the purpose of setting or curing the impregnating agents. Thus, for example, with an impregnating agent of the partially polymerized resin type, the temperature applied is sufficient to further the polymerization, resulting in the formation within the fibers of a urea formaldehyde resin of the desired physical characteristics.

One advantage inherent in this type of oven is that it provides for a very uniform and easily controlled heating of the yarn and moreover permits, if desired, of a gradual transition from one temperature to another, depending upon the characteristics of the impregnating agent and the particular effect desired. Another advantage is that if a yarn breaks, it immediately drops by gravity out of the zone of heat, thereby automatically preventing over-curing or burning, and visually apprising the operator of the particular yarn requiring his attention. Where necessary a device can be applied which will assist in lowering the yarn out of the oven in such a case.

Preferably each yarn as it emerges from the oven (or some other suitable point) passes in association with a stop motion device, such as that diagrammatically indicated by 152, including a vertical lever 153 carrying at its upper end the wire loop 154 which rests lightly on the yarn and through lever 155 controls microswitch 156. The construction is such that whenever the yarn breaks and lever 153 is no longer supported by the yarn, it will operate to close contact in microswitch 156, thereby causing electric current to travel through the leads 157 and 158 (Fig. 1).

Referring again to Fig. 3, the horizontal top portion 14 of section 12 is provided with upstanding stud 55 provided with the projecting shelf 56 secured between two lock nuts. The shelf 56 projects into the open jaw 57 of plate 58 pivotally carried by stud 61 attached to bracket 62, which in turn is riveted to the upright member 63. Plate 58 is normally urged in the direction indicated by arrow 64 by means of the tension spring 65 but is prevented from so doing by the latch 66 engaging end 67 of rod 68, which is also pivoted to plate 58 at the point 69. The latch 66 is pivotally secured at the point 71 to the upright 63 and is also pivotally secured at 72 to the plunger 73 of solenoid 74. Whenever the stop motion device 152 becomes operative and current flows through the leads 157 and 158, the solenoid 74 is energized, thereby lifting the latch 66 and permitting the plate 58 to move upwardly in the direction indicated by arrow 64. The same movement releases lever 15

thereby opening microswitch 76 and interrupting the flow of current through solenoid 74 until normal operation is re-established.

Whenever the stop motion device 152 is actuated by the breaking of a yarn, the particular impregnating section feeding said yarn will automatically and immediately be tilted upwardly about the pivot point 15 thereby instantly apprising the operator of the particular impregnating section requiring his attention. Inasmuch as section 12 is open at one side, the operator may, merely by manually tilting the section, still further expose the guide and roller mechanism and, if necessary, rethread the yarn within the impregnating device in the matter of a few seconds.

The foregoing description is for purposes of illustration and not of limitation and it is therefore our intention that the invention be limited only by the appended claims or their equivalents.

wherein it has been endeavored to claim broadly all inherent novelty.

We claim:

1. In apparatus for impregnating yarns and the like of the type including means for contacting yarns with an impregnating liquid adapted to simultaneously impregnate a number of yarns supplying impregnated yarns to one end of a heating oven and yarn winding means at the other end of said oven, the improved form of oven for such apparatus comprising sides and a roof defining an inverted, open bottom trough, a number of longitudinally extending, vertically oriented fins in said trough dividing said trough into a number of parallel open bottom channels, and means for heating the interior of said trough, said fins being formed as strips of sheet material carried adjacent their upper margins by transversely extending rods passing through oversized holes formed in said strips.
2. The improvement according to claim 1 in which the means for heating comprises electrical resistance heaters horizontally mounted beneath said roof.
3. The improvement according to claim 1 comprising, in addition, spacing means for said strips consisting of spool shaped members encircling said rods.
4. The improvement according to claim 1 in which said strips are provided with longitudinally extending channel shaped stiffeners adjacent their lower edges.
5. In apparatus for impregnating yarns and the like of the type including means for contacting yarns with an impregnating liquid operatively connected to an oven for curing such impregnated yarns, the improvement comprising a curing oven consisting of sides and a roof defining at least one horizontally disposed, inverted, open bottomed trough, means for heating the interior of said trough, means for feeding yarns from said means for contacting into one end of said trough, and means for winding cured yarn at the other end of said trough, said feeding and winding means being substantially on the same lever, whereby said impregnated yarns move through said trough in a substantially horizontal path, and in the event of breakage, the free ends automatically drop out of the zone of heat.
6. Improvement according to claim 5 in which the means for heating comprises electric resistance heaters horizontally mounted beneath said roof.
7. In apparatus for impregnating yarns and the like of the type including means for contacting yarns with an impregnating liquid adapted to simultaneously impregnate a number of yarns, operatively connected to an oven for curing such impregnated yarns, the improvement comprising a curing oven consisting of sides and a roof, a number of longitudinally extending, vertically oriented fins extending downwardly from said roof, dividing said oven into a number of parallel, horizontally disposed, open bottomed troughs, means for heating the interior of said troughs, means for feeding yarn from said means for contacting into one end of each said troughs, and means for winding cured yarn at the other end of each of said troughs, said feeding and winding means being substantially on the same level, whereby said impregnated yarns move through said troughs in a substantially horizontal path, and in the

event of breakage, the free ends automatically drop out of the zone of heat.

8. Improvement according to claim 7 in which the means for heating comprises electric resistance heaters horizontally mounted beneath said roof.

9. Apparatus according to claim 7 in which said fins are formed as strips of sheet material carried adjacent their upper margins by transversely extending rods passing through oversized holes formed in said strips.

10. Improvement according to claim 9 in which the means for heating comprises electric resistance heaters horizontally mounted beneath said roof.
